UNITED STATES PATENT OFFICE

163,802

STUFFED DOG

George Grooms, Ames, Iowa, assignor to Collegiate Manufacturing Company, Ames, Iowa, a corporation of Iowa

Application October 17, 1950, Serial No. 12,603

Term of patent 14 years

(Cl. D34—2)

To all whom it may concern:

Be it known that I, George Grooms, a citizen of the United States, residing at Ames, county of Story, and State of Iowa, have invented a new and original and ornamental Design for a Stuffed Dog, of which the following is a specification, reference being had to the accompanying drawings, forming a part thereof, in which—

I claim:

The ornamental design for a stuffed dog, as shown.

GEORGE GROOMS.
